UNITED STATES PATENT OFFICE

NORRIS T. OWEN, OF RAPID CITY, SOUTH DAKOTA

APPARATUS FOR USE IN BLOOD TRANSFUSION, INTRAVENOUS MEDICATION
AND THE LIKE

Application filed November 23, 1931. Serial No. 576,904.

This invention relates to apparatus for use in blood transfusion, intravenous medication and the like and has for one of its objects to provide a device of this character which will be simple in construction, comparatively inexpensive to manufacture and more efficient in use than those which have been heretofore proposed.

With the above and other objects in view which will appear as the description proceeds the invention consists in the novel details of construction and combinations of parts more fully hereinafter described and particularly pointed out in the appended claims.

Referring more particularly to the accompanying drawings forming a part of this specification in which like reference characters designate like parts in all the views:—

20 Figure 1 is a side elevational view of an apparatus constructed in accordance with the present invention, the parts being shown in their operative positions;

25 Figure 2 is a similar view as seen from the opposite side of the machine, the compressing member in this instance however being shown in the elevated position to which it is moved for the purpose of inserting or removing the deformable fluid conducting tube;

30 Figure 3 is a top plan view of the parts as shown in Figure 2;

Figure 4 is a transverse vertical sectional view taken approximately on the plane indicated by the line 4—4 of Figure 1; and

35 Figure 5 is a fragmentary sectional elevational view illustrating the registering mechanism, the means for actuating the same, and for locking the compressing member against retrograde movement.

40 Referring more particularly to the said drawings 10 indicates a suitable base from which rises the upright standard 11 provided with a vertical slot 12 in which is slidably mounted a block 13 receiving one end

45 of the horizontally disposed stud 14 on which is rotatably journaled a disk or wheel member 15. The said member 15 is provided with a suitable handle 16 by means of which the member may be manually rotated and it

50 further carries a plurality of compressor

rolls 17 journaled upon pins or shafts 18, as will be clear from the drawings.

Mounted upon the base 10 immediately below the rotatable member 15 is a strap 19 having the upwardly extending arms 20 which receive a block or supporting member 21 which is or may be of rubber or other similar yielding material. The upper ends of the arms 20 are slotted or recessed as at 22 for the free reception of a deformable conduit 21, which may conveniently take the form of a rubber tube. The said tube is provided with spaced stop members or projections 24 which are here shown as comprising rings or bands of rubber which may be vulcanized or otherwise rigidly secured to the outer surface of the tube, as will be readily understood. The said members 24 are preferably so spaced that when the tube is positioned within the recesses 22 with the members 24 upon the outside of the arms 20, the portion of the tube between the members 24 will be under tension as indicated in broken lines in Figure 2. Each end of the tube 23 may be provided with a suitable hollow needle 25 of well known form for injection into the veins of a patient, and of the donor in case of blood transfusion.

The traveling compressor member 15 together with its presser elements 17 normally occupies the position shown in Figure 1 during operation but for the purpose of removal and replacement of tube 23 it is adapted to be elevated to the position shown in full lines in Figure 2. This is accomplished through manually lifting the member 15, which owing to its slideable mounting by means of the block 13 in the slot 12, permits of such raising movement. In order to maintain the parts in their elevated positions the standard 11 is preferably provided with a transverse bore 26 in which is mounted a ball or other detent member 27, normally pressed against the surface of the block 13 by a spring 28, the pressure of which may be adjusted by the threaded plug 29, as will be readily understood. The block 13 is provided with a depression or recess 30 into which the ball 26 may snap when the parts reach the positions shown in full lines in

55

60

65

70

75

80

85

90

95

100

Figure 2, whereby the member 15 will be held in its elevated position.

A coil spring 31 is interposed between the top of the block 13 and a slidable follower 32, also mounted in the slot 12 for the purposes of providing a yielding downward pressure upon the block 13, which pressure will maintain the compressor elements 17 in constant operative contact with the conduit 23 when the parts are in their normal operative positions shown in Figures 1 and 4. An adjustment screw 33 is threaded into a bridge member 34 which spans the top of the standard 11 and its lower end bears against the follower 32, thereby providing a ready means for varying the pressure exerted by the spring 31 and the consequent pressure exerted by the presser elements 17 upon the conduit 23, as will be readily understood. The slidable mounting of the traveling compression member 15, together with the yieldability afforded by the spring 31, also compensates for any inaccuracies in the supporting surface of the block 21 and insures constant positive contact between the compressor elements 17 and the conduit 23 with sufficient pressure to fully compress the tube and prevent the backward flow of fluid within the tube.

The conduit 23 as above stated preferably takes the form of a rubber tube and it is preferred to employ a tube having relatively thin walls, the thickness thereof being such that the tube will collapse under external atmospheric pressure in the event of clogging of the supply side of the apparatus. Such collapse is indicated at 23' at the left hand side of Figure 1 and serves as a visible indication that the apparatus is not functioning properly.

In the transfusion of blood, as well as in intravenous medication, it is of course desirable to know the amount of fluid which has passed through the machine and for this purpose there is provided in connection with the present device a suitable mechanism 35 which as here shown comprises a well known form of registering counter adapted to be actuated through oscillating movements of its shaft 36, see Figs. 2, 3 and 5. The said shaft is provided at one end with a suitable knob 37 by means of which the device may be manually set to zero while the opposite end of the shaft carries arm 38 which normally occupies substantially the position shown in Figures 2 and 5 under the influence of a spring or other similar device contained within the counter 35. The said arm 38 is disposed in the path of travel of a trip element 39 carried by the traveling compressing member 15, so that at each revolution of the said member the element 39 will contact with and move the arm 38 in a clockwise direction as viewed in Figure 5, thereby moving the counter-shaft 36 a predetermined distance and causing registration by the counting

mechanism of such revolution of the traveling member. Since the capacity of the conduit may be readily ascertained, it is an easy matter to translate the registrations of the counting mechanism 35 into volume of fluid passed through the tube. 70

In blood transfusion operations particularly, it is desirable that retrograde movement of the member 15 with a consequent reversal of flow of blood within the conduit be prevented. The counting mechanism 35 here illustrated provides an effective means for accomplishing this, since its construction is such that the movement of its arm 38 in a counterclockwise direction, as viewed in Figure 5, is positively stopped when it reaches the position shown in full lines in the said figure. It thus results that although the element 39 may move the arm 38 in a clockwise direction to pass the same when the traveling member 15 is being rotated in the proper transfusing direction, should the said member 15 be moved in a reverse direction the element 39 will engage the arm 38, and since reverse movement of the latter is limited, it will act as an effective stop to limit the retrograde movement of a compressing member 15. 80

It may however be desirable at some time to permit such retrograde movement, as for instance during preliminary operations of blood transfusion, during cleaning or sterilization of the apparatus or tube, and in some instances in connection with intravenous medication. For the purpose of rendering ineffective the stop mechanism just described the arm 38 is provided with an extension 40, and is adapted to be moved to the dotted line position shown in Figure 5 where the said extension 40 may be engaged by the element 41 of a manually operable slide 42 mounted upon the base 10. Obviously when the sliding member 42 is moved from its full line to its dotted line position shown in Figure 5, its portion 41 will engage over the extension 40 of lever 38 and serve to hold the latter in the dotted line position, whereby it is clear of the member 39 so that the rotating member 15 together with its compression elements 17 may be freely rotated in either direction. Of course during such operation, the counting mechanism 35 will not be actuated. 105 110 115

The operation of the machine will be immediately apparent to those skilled in the art, it being understood that in blood transfusion, for example, after the left hand needle 25 (Fig. 1) has been introduced into the vein of the donor, and the member 15 given a few turns by means of its handle 16 to clear the tube 23 of air, the right hand needle 25 may be injected into the vein of the patient, whereupon further rotation of the member 15 will cause the rollers 17 to produce traveling deformation of the tube, forcing 120 125 130 135

the blood therethrough in the well known manner.

Blood of course is a highly coagulable substance, especially when in contact with the air; but such contact is wholly avoided with the present apparatus, thereby eliminating the injection of clots into the veins of the patient, with possible fatal results. Furthermore, the apparatus has no complicated valves requiring exceptionally careful cleaning and sterilization in order to prevent the possibility of clots remaining in them from previous operations. The present tubes 23 and needles 25 are the only parts requiring cleaning, and they present no particular difficulty. In fact the tubes 23 are so relatively inexpensive that they may be discarded after each operation, if necessary.

The walls of the tubes 23 being quite thin, as above explained, prohibits the use of clamps to hold the tubes in place, as these would collapse or constrict the tubes. However, the projections 24 formed on their outer surfaces have been found in actual practice to form with the slotted arms 20 an effective means for positioning the tubes. The latter are freely receivable in the slots 22 of the arms without constriction, and the engagement of the members 24 with the surfaces of the arms prevents longitudinal creeping of the tubes under the action of the traveling rolls 17.

While one form of the invention has been illustrated and described it is obvious that those skilled in the art may vary the details of construction as well as the precise arrangement of parts without departing from the spirit of the invention, and therefore it is not wished to be limited to the above disclosure except as may be required by the claims.

40 What I claim is:

1. In a blood transfusion apparatus and the like having a support, a deformable conduit in juxtaposition with said support, and means movable along said conduit to compress the same against said support and thereby produce traveling deformation of the conduit, the combination of means for yieldingly mounting said compressing means relative to said conduit.

50 2. In a blood transfusion apparatus and the like having a support, a deformable conduit in juxtaposition with said support, and means movable along said conduit to compress the same against said support and thereby produce traveling deformation of the conduit, the combination of means for mounting said compressing means for rectilinear movement toward and from said support.

60 3. In blood transfusion apparatus and the like having a support, a deformable conduit in juxtaposition with said support, and a traveling member provided with means movable along said conduit to compress the same against said support and thereby produce traveling deformation of the conduit, the

combination of means for yieldingly mounting said traveling member for substantially vertical movement toward and from said support; and means for retaining said member elevated when moved away from said support. 70

4. In blood transfusion apparatus and the like having a support, a deformable conduit in juxtaposition with said support, and a traveling member provided with presser elements movable along said conduit to compress the same against said support and thereby produce traveling deformation of the conduit, the combination of means for mounting said traveling member for free movement toward and from said support; and adjustable resilient means for varying the pressure exerted by said member and its presser elements upon said conduit. 80

5. In blood transfusion apparatus and the like having a support, a deformable conduit in juxtaposition with said support, and a traveling member provided with means movable along said conduit to compress the same against said support and thereby produce traveling deformation of the conduit, the combination of a slotted standard adjacent said support; a block slidably mounted in the slot in said standard for mounting said traveling member, whereby it may move freely toward and from said support; a spring normally urging said block and member toward said support; and a detent for retaining said block and member away from said support against the action of said spring. 90

6. In blood transfusion apparatus and the like having a support, a deformable conduit in juxtaposition with said support, and means movable along said conduit to compress the same against said support and thereby produce traveling deformation of the conduit, the combination of means for limiting retrograde movement of said compressing means to prevent reverse flow of fluid in said conduit. 100

7. In blood transfusion apparatus and the like having a support, a deformable conduit in juxtaposition with said support, and a traveling member provided with means movable along said conduit to compress the same against said support and thereby produce traveling deformation of the conduit, the combination of a stop member positioned in the path of travel of a portion of said traveling member, said stop member being yieldable to permit free passage of said traveling member in one direction, but engageable by said traveling member portion to limit movement thereof in the opposite direction 110 to prevent reverse flow of fluid in said conduit.

8. In blood transfusion apparatus and the like having a support, a deformable conduit in juxtaposition with said support, and a 120

- traveling member provided with means movable along said conduit to compress the same against said support and thereby produce traveling deformation of the conduit, the combination of an arm normally in the path of and yieldable to a portion of said traveling member as it moves in one direction, said arm being engageable by said traveling member portion upon movement in the opposite direction to limit such retrograde movement and prevent reverse flow of fluid in said conduit; and means for holding said arm out of the path of said traveling member to permit the latter to move freely in either direction.
9. In blood transfusion apparatus and the like having a support, a deformable conduit in juxtaposition with said support, and a traveling member provided with means movable along said conduit to compress the same against said support and thereby produce traveling deformation of the conduit, the combination of an arm normally in the path of and yieldable to a portion of said traveling member as it moves in one direction, said arm being engageable by said traveling member portion upon movement in the opposite direction to limit such retrograde movement and prevent reverse flow of fluid in said conduit; an extension carried by said arm; and means operable at will to engage said extension and hold said arm out of the path of said traveling member to permit the latter to move freely in either direction.
10. In blood transfusion apparatus and the like having a support, and movable compressing means disposed in co-operative relation to said support; a deformable fluid-conducting conduit interposed between said support and compressing means, said conduit being collapsible under external atmospheric pressure to indicate failure of fluid transmission.
11. In blood transfusion apparatus and the like having a support, and movable compressing means in juxtaposition with said support, a resilient fluid-conducting conduit interposed between said support and compressing means, the walls of said conduit being of such thickness as to permit the collapse of said conduit upon operation of said compressing means to indicate failure of fluid transmission.
12. In blood transfusion apparatus and the like having a support, a deformable conduit in juxtaposition with said support, and means movable along said conduit to compress the same against said support and thereby produce traveling deformation of the conduit, the combination of a pair of spaced members for positioning said conduit in co-operative relation to said support and compressing means; and means carried by the conduit engaging said members to prevent longitudinal creeping of the conduit.
13. In blood transfusion apparatus and the like having a support, a deformable conduit in juxtaposition with said support, and means movable along said conduit to compress the same against said support and thereby produce traveling deformation of the conduit, the combination of spaced members for positioning said conduit in co-operative relation to said support and compressing means, said members having apertures for freely receiving said conduit without constriction; and projections carried by the conduit engaging said members to prevent longitudinal creeping of the conduit.
14. In blood transfusion apparatus and the like having a support, a deformable resilient conduit in juxtaposition with said support, and means movable along said conduit to compress the same against said support and thereby produce traveling deformation of the conduit, the combination of spaced members for positioning said conduit in co-operative relation to said support and compressing means, said members having apertures for freely receiving said conduit without constriction; and projections carried by the conduit engaging said members to prevent longitudinal creeping of the conduit, said projections being so positioned upon said conduit as to cause the portion of the conduit lying between said spaced members to be held under tension.
- In testimony whereof I affix my signature.
- NORRIS T. OWEN.
